UNITED STATES PATENT OFFICE.

THOMAS H. SEELEY, OF MELDEN, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed December 21, 1922. Serial No. 608,292.

The invention relates to wax thread lock stitch sewing machines such as are used in attaching outsoles to shoes.

In doing certain classes of work, as for instance, in sewing the leather outsole to a shoe, it is sometimes desirable to groove the sole for the reception of the stitches, and for this purpose the needle guide has heretofore been provided with a cutting or indenting edge for forming a stitch receiving groove in the work. In doing certain other classes of work as, for instance, in attaching rubber outsoles to shoes, grooving of the work is objectionable. It has been necessary, therefore, in order to adapt the machine for doing both classes of work to provide two needle guides, one with cutting edges and one without, and to change the needle guides in changing from one class of work to the other. This is objectionable, particularly in the case of the machine used for shoe repair work, owing to the delay and inconvenience incident to frequently changing from one needle guide to the other, and is further objectionable owing to the danger of losing or misplacing the needle guide which is out of use.

The present invention avoids the above objections to the use of a needle guide having groove-forming edges by the provision of actuating mechanism therefor, which may be set or adjusted by the operator to cause the guide to be pressed against the work and thus form a stitch receiving groove therein, or may be set or adjusted to cause the advance stroke of the guide to terminate before its edges engage or indent the work and thus avoid grooving the work without the necessity of changing the guide.

The preferred form of the invention is shown in the accompanying drawings in which Fig. 1 is a left hand side elevation showing so much of a lock stitch wax thread sewing machine as is necessary to illustrate the application of the invention thereto, Fig. 2 is a plan view of the mechanism shown in Fig. 1, Fig. 3 is a detailed front view of the needle guide and its segment, Fig. 4 is a detailed side elevation of the same, Fig. 5 is a detailed plan view of the seam sewed when the needle guide is actuated to groove the work, Fig. 6 is a sectional view through the seam, Fig. 7 is a view similar to Fig. 1 showing the position of the parts when the needle is at the end of its retracting stroke, and Fig.

8 is a view similar to Fig. 1 showing the parts 55 adjusted to avoid grooving the work.

In the drawings the invention is illustrated as applied to an outsole lock stitch sewing machine having the general construction and mode of operation of the machine shown and described in Patent No. 473,870, dated April 26, 1892, and known as the Goodyear rapid outsole stitcher. The machine is provided with stitch forming and work feeding devices such as shown and described in said patent, 60 and including the work support 2 and the curved hook needle 4 which is secured in the needle segment 6. The needle segment is oscillated by a lever 8 actuated by a cam on the cam shaft of the machine and provided 65 at its forward end with a segment 10 engaging the needle segment.

The needle guide 12 is provided with groove cutting edges 14 on opposite sides of the needle and is secured to the segment 16. The 70 mechanism for oscillating the needle guide segment is so constructed that it may be readily adjusted by the operator to cause the needle guide to either groove the work or to avoid grooving the work. As shown the 75 mechanism for oscillating the needle guide comprises a bell crank lever 18, one arm of which is provided with a segment 20 engaging a pinion 22 which in turn engages the teeth of the needle guide segment. The 80 other arm of the bell crank lever is connected by a link 24 with one arm of a lever 26, the other arm of which is connected by a link 28 with a block 30 secured to the needle actuating lever 8. Through these connections 85 the needle guide is advanced toward the work during the upward movement of the lever 8 which gives the needle its forward stroke and is retracted during the downward movement 90 of the lever which gives the needle its retraction stroke. The levers and links are so arranged and proportioned that the needle guide will advance rapidly into position close to the work during the first part of the forward stroke of the needle and will have

comparatively little forward movement during the latter part of the forward stroke of the needle. On the reverse stroke of the needle the needle guide will remain close to the work during the first part of the stroke and will be retracted with the needle during the last part of its stroke after it has withdrawn from the work.

In order that the forward stroke of the needle guide may be varied to cause it to either groove or avoid grooving the work means is provided for adjusting the pivotal connections between the link 28 and the lever 26. As shown this means comprises a pivot block 32 which is pivotally connected to the end of the link and is adjustably secured to the lever 26 by an adjusting screw 34. The front end of the screw is slotted to receive a screw driver so that the operator may quickly and conveniently rotate the screw to adjust the pivot block either into the position indicated in Figs. 1 and 7 or into the position indicated in Fig. 8. When the block is located as indicated in Figs. 1 and 7 the forward stroke of the needle guide will be such that it is pressed against the work, thus causing the cutting edges 14 to cut a stitch receiving groove in the work as indicated in Figs. 3 to 6. When the block is adjusted into the position indicated in Fig. 8 the forward stroke of the needle guide will be shortened so that the groove cutting edges will not be pressed against the work and thus the needle guide will be so operated as to avoid grooving the work.

In order that the needle guide may be pressed yieldingly against the work when acting to cut a needle receiving groove therein, and may thus accommodate itself to different thicknesses of work, the link 24 is provided with a spring through which motion is transmitted from the lever 26 to the lever 18. As shown the link comprises a sleeve 36 pivotally connected to the lever 26, a rod 38 pivotally connected to the lever 18, and passing through the sleeve, and a spring 40 with in the sleeve interposed between a collar 42 on the rod and an adjustable screw plug 44 in the upper end of the sleeve. By adjustment of the plug 44 the tension of the spring 40 may be adjusted to regulate the pressure with which the needle guide is pressed against

the work. By adjustment of the rod 38 through its pivot stud 46 the stroke of the needle guide with relation to the work may be varied to secure its proper operation under the different adjustments of the pivot block 32.

While it is preferred to employ the construction and arrangement of parts shown and described in applying the invention to the machine of the patent above referred to it will be understood that this construction and arrangement is not essential and may be varied or modified as found desirable or best suited to the construction and mode of operation of the machine to which the invention is to be applied.

What is claimed is:

1. A sewing machine having, in combination, stitch forming devices including a hook needle, a needle guide having an edge for forming a stitch receiving groove in the work, and means for actuating the needle guide in varying ranges of movement to press the needle guide against the work, or to avoid pressing it against the work.

2. A sewing machine having, in combination, stitch forming devices including a hook needle, a needle guide having an edge for forming a stitch receiving groove in the work, actuating mechanism for the needle guide, and means for adjusting said mechanism to impart varying ranges of movement to the needle guide to press the needle guide against the work or to avoid pressing it against the work.

3. A sewing machine having, in combination, stitch forming devices including a hook needle, a needle guide having an edge for forming a stitch receiving groove in the work, actuating mechanism for the needle guide adjustable to impart varying ranges of movement to the needle guide to press the needle guide yieldingly against the work or to avoid pressing it against the work.

THOMAS H. SEELY.
